JOSEPH DE ROSE, OF PHILADELPHIA, PENNSYLVANIA.

WATER-CLOSET.

Application filed November 3, 1928. Serial No. 317,074.

This invention relates to water closets and, more particularly to that class or type which embodies a flush-water chamber under control of valve mechanism adapted for operation by the closet seat whereby thorough flushing is automatically effected.

The primary object of the present improvements is to provide a compact flushing apparatus more particularly, although not essentially, adapted to the flush-water chambers of the above referred to type of closet bowls.

Another object is the provision of a flushing apparatus for installation in the flush-water chambers of closet bowls with direct connection into the service supply pipe.

A further object is to provide a compactly arranged, practically noiseless and simply constructed, automatic flushing apparatus which is free of any tendency to "siphonic" action incident to flushing of the closet bowl or disturbance in the service supply such as obtains on opening a local faucet while the closet is in use.

A still further object is the provision of a water closet which is fool-proof and that automatically functions each time pressure is applied to—and removed from—the closet seat, thereby obviating all necessity for manual flushing and the unsanitary conditions attending forgetfulness in this connection.

With the foregoing and other objects in view, this invention essentially consists in the novel construction, combination and arrangement of parts constituting the matters hereinafter specifically described and illustrated by the accompanying drawings which form a part hereof; but it is to be understood that changes, variations and modifications, may be resorted to without departing from the scope of said invention or sacrificing any of the foregoing recited objects and advantageous features.

In the drawings:—

Fig. I is a vertical sectional view illustrative of one complete physical example of my invention; and,

Fig. II is a relatively enlarged vertical section through the novel flushing apparatus and

associated parts, with the control valve in the "shut-off" position.

Referring first, more particularly, to Fig. I a typical water closet bowl is comprehensively designated by the numeral 5, the same affording a water seal 6 and outlet 7 to which the sewer connection 8 is attached in conventional manner. The bowl 5 is also characterized by an annular chamber 9 about its top, designed to serve as a reservoir for the flushing water; said chamber having communication into a subjacent distributor channel 10, by way of a port 11 in the separating wall or partition 12, the flushing water discharging into the bowl 5 through perforations 13, in the customary way.

For the purpose of controlling the filling of, and flushing-discharge from the chamber 9, I make use of the novel flushing mechanism or apparatus, constituting the fundamentals of the present invention, and now to be described in detail.

Conveniently fitted to the upper end of the service pipe 14—as by screw threading—is a tubular extension 15 of a length to extend above the horizontal median of the flush-water chamber 9, whereat it is exteriorly screw-threaded for secure attachment of a hollow closure or cap 16, having a series of inflow ports 17 through the lower face or portion thereof. This closure cap 16 is provided with a central interior embossment 18, functional as a limiting stop controlling the lift of a puppet check valve 19, guided in its rise and fall by feathers or legs 20 slidably freely within the bore at the upper end of the tubular extension 15, while the latter is suitably beveled at 21 to provide a seat for said valve.

Concentric with the aforesaid extension 15—and upper end of the service pipe 14—is a tubular fitting 22 of larger diameter that affords an annular intervening space 23 for a purpose later on explained. This fitting 22 is provided at the upper end with a dished flange 24 affording a peripheral rib seat 25, as well as having a series of openings 26 therethrough communicating into the flush-water discharge port 11. It is noticeable the tubular-fitting dished-flange 24 is somewhat

larger in diameter than the discharge port 11, so as to seat in a counter-bore 27 formed thereabout in the separating wall 12, with interposition of a suitable sealing washer 28, 5 while the tubular fitting 22 extends downwardly through an aligned opening 29 in the lower wall of the distributor channel 10. The fitting 22 is externally screw-threaded to receive a lock nut or nuts 30 whereby it is secured in place and rendered leak-proof by aid of a suitable sealing gasket 31, as will be clearly understood by those conversant with the art. Threadedly engaging the outer or lower end of the tubular fitting 22 is a reducer 10 nipple 32, the smaller section 33 whereof is a snug fit on the service pipe 14, and it is externally screwed for reception of a conventional gland nut 34 and packing 35, whereby the service connection is made water tight. 15 Slidably engaging the tubular service extension 15, intermediate the hollow closure cap 16 and the dished flange 24 of the fitting 22, is a sleeve member 36 that is normally urged upward by a spring 37 under compression, freely fitting the annular space 23 with capacity for adjustment by the reducer nipple 32 in opposition to the closure cap 16, in an obvious manner. This slidable sleeve or double-acting member 36 is provided at the 20 upper end with a dished flange 38 having secured therein an appropriate gasket 39 for co-operation with the lower perforate face of the hollow cap 16 in normally closing the discharge ports 17. At its lower end, the sleeve member 36 is equipped or formed with a disk valve member 40 adapted to engage the hereinbefore described rib-seat 25 of the tubular fitting dished flange 24; and, in order to ensure water-tight closure of the discharge 25 openings 26 during filling of the chamber 9 with flush-water, the valve member 40 is fitted with a suitable washer 41, held in place by a clamp nut 42, in accordance with known procedure. 30 Downward movement of the sleeve member 36 is effected through the medium of a perforate bell 43 having a vertically directed stem 44 slidably through a stuffing-box 45 forming part of a cupped attachment 46, 35 sealed in an aperture 47 of the top wall of the flush-water chamber 9 by a compressible gasket 48 and conventional securing means 49. Obviously the perforate bell 43 is normally maintained elevated by the compression 40 spring 37 to thereby support the closet seat 50 slightly elevated relative to the bowl 5; said seat being hinged at 51 to a conventional device 52, sealed in the rear part of the aforesaid flush-water chamber 9. 45 The use and operation of my novel flushing apparatus is as follows:—As the seat 50 is depressed by a user of the closet the resistance of the compression spring 37 is overcome, with the result that the stem 44 and perforate 50 bell 43 are moved downward carrying with them the sleeve member 36. As a consequence the dished flange 38 is moved away from the closure cap 16 to uncover the discharge ports 17, thereby permitting service water pressure to elevate the check valve 19 and flow 70 through said ports—as well as via the perforate bell 43 into the annular flush-water chamber 9. At the same time, the disk valve member 40 is forced into contact with the co-operative peripheral rib seat 25 of the fitting 22 thereby, temporarily, closing discharge of water, by way of the openings 26 and port 11, into the distributor channel 10 and from thence to the bowl 5. With closure of the port 11, as just described, a certain amount 75 of air will be trapped in the flush-water chamber 9 and compressed by the intrushing water from the service pipe 14, the flow of water continuing until an equalization of pressure obtains. When the seat 50 is released, incident to the user rising therefrom, the compression spring 37 instantly functions to elevate the sleeve member 36 with resultant opening of the discharge port 11 and concurrent closure of the inflow ports 17; where- 80 as simultaneous elevation of the perforate bell 43 takes place with concurrent raising of the seat 50 by the stem 44 to normal in- 85 active or out of use location. Incident to the movements set forth, the water collected in the chamber 9 is expelled via the openings 26, and discharge port 11, into the distributor channel 10 for forced dissipation through the perforations 13 about the closet bowl 5, 90 breaking the water seal 6, and effectively flushing and siphoning out the contents of said bowl via outlet 7, to sewer connection 8, such operation being expedited under pressure of the air, previously trapped in the chamber 9, as described above in connection 95 with the flush-water filling period. Incidentally it is to be particularly noted that the check valve 19 will always be subject to service pressure, with the result that said check valve 19 normally abuts the emboss- 100 ment 18, or is lifted from its seat 21. This feature I deem of vital importance in counter-acting any possibility of siphonic action setting up through the apparatus—when the seat 50 is released—consequent upon the 105 opening of a faucet, locally or otherwise, in the service connection while the closet is in use. It will be obvious that, instantly the balance of pressure above and below the check valve 19 is disturbed, said valve will 110 instantly seat itself under the action of the compressed air in the chamber 9 assisted by its own weight or gravity; so that, on release of the seat 50, the sequence of operations above set forth are positively and automatically ensured. 115 Furthermore attention is directed to the fact that my novel flushing apparatus can be readily installed and quickly removed for inspection or replacement through the aid 120 125 130

of the nipple 32, lock nut 30 and attachment 46.

From the foregoing it will be apparent that I have provided a direct-acting flushing apparatus for water closets which is simple in construction, automatic in action, and devoid of any parts liable to become deranged or get out of order under constant use or careless misuse.

Having thus described my invention, what I claim is:—

1. The combination with a water closet having a flush-water chamber about its top with a subjacent distributor channel, and a pivoted seat; of a flushing apparatus including a yieldingly-sustained double-acting valve device interposed in the flush-water chamber, and aligned co-operative means enclosing an instrumentality preventive of siphonic action normally sustaining the closet seat elevated but serving when depressed to move the valve device from service shut-off position into chamber-filling location.

2. The combination with a water closet having a flush-water chamber about its top with a subjacent distributor channel, and a pivoted seat; of a flushing apparatus including a yieldingly-sustained double-acting valve device interposed in the flush-water chamber, an aligned co-operative perforate bell having a stem normally sustaining the closet seat elevated but serving when depressed to move the valve device from service shut-off position into chamber-filling location, and a check valve subject to trapped air pressure effective to prevent siphonic action through the apparatus.

3. The combination with a water closet having a flush-water chamber about its top with a subjacent distributor channel, and a pivoted seat; of a flushing apparatus including a yieldingly-sustained sleeve member having valve flanges serving to control supply and discharge of flush-water into and out of the aforesaid chamber, an axially aligned co-operative perforate bell with a stem normally sustaining the closet seat elevated but serving when depressed to move the valved sleeve from service shut-off into chamber filling location, and a puppet check valve in the service outlet subject to trapped air pressure effective to prevent siphonic action through the apparatus.

4. In a water closet having a flush-water chamber about its top with a subjacent distributor channel, the combination of a flushing apparatus operable by the closet seat and comprising, a tubular extension connecting the service supply pipe into the flush-water chamber with a hollow closure cap having discharge ports through its lower wall, a tubular fitting concentric with the extension affording an annular space about the latter and having an apertured flange seating in

the closet wall separating the aforesaid chamber and channel, means whereby the tubular fitting is secured in place, a reducer coupling said fitting water-tight to the service supply pipe, a sleeve having end flanges serving as valve members slidable on the tubular extension, yielding means intermediate the flanged sleeve and a shoulder in the reducer normally holding said sleeve against the hollow cap to effect closure of the discharge ports therein, and a perforate bell seating on the upper flange of the sleeve with a stem in engagement with the closet seat, for the purpose specified.

5. In a water closet having a flush-water chamber about its top with a subjacent distributor channel, the combination of a flushing apparatus operable by the closet seat and comprising, a tubular extension connecting the service supply pipe into the flush-water chamber with a hollow closure cap having discharge ports through its lower wall, a tubular fitting concentric with the extension affording an intervening annular space, said fitting having an apertured flange, with a peripheral rib, seating in a counter-bore of an outlet port connecting the flush-water chamber to the distributor channel; means securely sealing the tubular fitting in place; a reducer nipple and gland device coupling said fitting water-tight to the service supply pipe; a sleeve slidable on the tubular extension having upper and lower end flanges, the former of which is dished and co-operative with the hollow closure cap aforesaid and the latter adapted by movement to seat on the tubular fitting flange peripheral rib; a spring under compression intermediate the flanged sleeve and a shoulder in the reducer nipple normally holding the sleeve dished flange against the hollow cap to close the discharge ports therein; and a perforate bell, seating in the sleeve dished flange, having an axial stem in contact with the closet seat, for the purposes specified.

6. In a water closet having a flush-water chamber about its top with a subjacent distributor channel, the combination of a flushing apparatus operable by the closet seat and comprising; a tubular extension connecting the service supply pipe into the flush-water chamber with a hollow closure cap having discharge ports through its lower wall; a puppet check valve freely fitting the upper end of the tubular extension and limited as regards lift by a central embossment in the closure cap; a tubular fitting concentric with the extension affording an intervening annular space, said fitting having an apertured flange, with a peripheral rib, seating in a counter-bore of an outlet port connecting the flush-water chamber to the distributor channel; means securely sealing the tubular fitting in place; a reducer nipple and gland device coupling said fitting water-tight to

the service supply pipe; a sleeve slidable on the tubular extension having upper and lower end flanges, the former of which is dished and co-operative with the hollow closure cap aforesaid, and the latter adapted by movement to seat on the tubular fitting flange peripheral rib; a spring under compression intermediate the flanged sleeve and a shoulder in the reducer nipple normally holding the sleeve dished flange against the hollow cap to close the discharge ports therein; and a perforate bell, seating in the sleeve dished flange, having an axial stem in contact with the closet seat, for the purposes specified.

In testimony whereof, I have hereunto signed my name at Philadelphia, Pennsylvania, this 23rd day of October, 1928.

JOSEPH DE ROSE.
